(57) CLAIM

The ornamental design for an optical disc drive, as shown and described.

DESCRIPTION

FIG. 1 is a perspective view of an optical disc drive showing my new design;

FIG. 2 is a front view of FIG. 1;

FIG. 3 is a top view of FIG. 1, the bottom view being an inverted image of the top view;

FIG. 4 is a left side view of FIG. 1, the right side view being a mirror image of the left side; and,

FIG. 5 is a rear view of FIG. 1.
